METHOD AND MEANS FOR VARYING THE COUNT OF ROVING IN CARDING MACHINES

Hubert G. Duesberg, Leominster, and Cecil A. Potter, Templeton, Mass., assignors to Duesberg-Basson of America, Inc., Fitchburg, Mass., a corporation of Massachusetts

Application June 29, 1951, Serial No. 234,382

7 Claims. (Cl. 19—106)

1

This invention relates to carding machines. It is particularly concerned with an improvement in the means and method used with a woolen carding machine for controlling the count of the roving produced by the carding operations.

In the disclosure hereinafter and in the drawings reference will be made to a woolen carding machine but it is to be understood that the method and mechanism used in controlling and varying the roving count is applicable to carding machines designed for use with other types of fibers.

The present invention is shown in connection with a conventional woolen card in which there is a breaker card (not shown) and a finisher card including a conventional tape condenser for producing the roving in the usual form. As is well understood in the carding machine field it has always been difficult to maintain the count of the roving exactly as required. If it should run heavy or light then it has been necessary to change the rate of feed at the hopper in which case the results of the change of feed will not be known for some minutes thereafter as the fibers move slowly through the carding elements to the tape condenser. Other expedients have been used which have required stopping the card and changing gears at selected locations which will have the effect of varying the roving count. In all of the prior methods, however, it has been impossible to foretell with accuracy the resulting effect on the roving count until sometime after the change in feeding rate has been made, or the machine has been stopped for gear changing with resulting loss of production. Thus, it has been impossible to have any truly fine accurate control of the roving count that may be changed or modified while the machine is in operation and which will produce the desired effect almost immediately, thereby permitting the operator to promptly sample and test the roving for count accuracy.

Accordingly, it is an object of this invention to provide a method of procedure and means for carrying out that procedure whereby the count of the roving emerging from the tape condenser may be maintained continuously and with accuracy at the particular figure required while the carding machine remains in operation. The method involves the concept of varying the speed between the last cylinder of the finisher card and the doffer by infinitely small increments so that the webb removed by the comb from the doffer may be varied in weight per unit

5 of length the exact degree required to bring the count of the roving to the correct figure if it has been found that the roving coming from the tape condenser has departed from the proper count.

The invention also includes the particular mechanism that has been devised to bring about the infinite variation in rotating speeds between the last cylinder and the doffer of the finisher card. The mechanism that varies the doffer speed with respect to the last cylinder does not, however, cause any variation in relative speeds between the doffer and the tape condenser.

10 These and other objects of the invention will become more apparent as the description proceeds with the aid of the accompanying drawings in which:

Fig. 1 is a side elevation of a major portion of the finisher card including the last cylinder, doffer and tape condenser.

15 Fig. 2 is an enlarged side elevation showing in greater detail the left hand portion of the machine shown in Fig. 1.

Fig. 3 is a plan view of the driving mechanism 20 of the cylinders and doffer including the means for varying the relative speed between the cylinder and doffer by infinite increments.

25 First referring to Fig. 1, the elements of the carding machine shown therein comprise the conventional cylinders 2 and 4, the doffers 6 and 8 and the usual workers W, strippers S and fancies F which have not been numbered as they 30 constitute no part of the invention.

35 To the left of doffer 8 is the tape condenser, generally referred to at 10, which produces the roving which is subsequently wound on spools 12.

The power for driving the entire finisher card unit is provided by an electric motor 14 and between this motor and the drives to the elements is a variable speed mechanism 16. The output shaft 17 of the variable speed mechanism 16 drives cylinders 4 and 2 as well as doffer 6. The cylinders are driven through belts 18 while doffer 8 is driven through a separate chain drive 20 which in turn feeds its power 40 through a second variable speed mechanism 22 and thence through suitable gearing, that will be more particularly described hereinafter, to the doffer 8 and tape condenser 10.

45 Referring now to Figs. 2 and 3, the driving mechanism that is utilized in operating the elements and which enables the method of the invention to be carried out comprises the motor 14 driving the variable speed mechanism 16 50 which may be of any conventional type, such as,

55

for example, the so-called Reeves drive in which the input and output pulleys, connected by a belt, are spread and contracted in a cooperating manner to produce an infinite number of variations of speed between the motor 14 and the output shaft 17. It will be understood, of course, that there are numerous commercial variable speed drives of the Reeves type on the market, and any one having suitable characteristics may be used provided it is of the adjustable infinite ratio type.

The outboard end of shaft 17 is carried by a suitable bearing 26 and on the shaft are a multiple grooved pulley 28 and a gear 30. Pulley 28 drives the plurality of belts 18 which travel over a corresponding number of large grooved pulleys 34 mounted on shaft 35 of cylinder 4.

Although not shown it will be understood that in the conventional manner a belt on a pulley on the opposite side of cylinder 4 drives a corresponding pulley on cylinder 2 so that the two cylinders run at identical speeds. Doffer 6 in turn is driven by a small pulley 36, belt 38, pulley 40 and cooperating gears 42 and 44. This arrangement produces a substantial reduction in the rotational speed of doffer 6 in relation to cylinder 2.

Gear 30 drives chain 20 and gear 48 carried by shaft 50 of the second variable speed mechanism 22. The variable speed drive 22 likewise being based on the principles of the Reeves drive has an infinite number of speed ratios which may be controlled by actuation of a hand wheel 52 which when rotated in one direction or the other will change by corresponding degrees the speed of output shaft 54 in relation to the input shaft 50. Suitable additional gear reduction mechanism may be included in the variable speed drive housing as at 57 but whether or not speed reduction gearing is included it will have no additional effect in varying the relative speeds between shafts 50 and 54 which changes are directly under the control of hand wheel 52.

The various elements that are driven by shaft 54 are as follows. A gear 56 mounted on shaft 54 drives gear 58 which meshes directly with gear 60 which is mounted and fixed on shaft 62, which shaft carries a smaller gear 64 which meshes with larger gear 66 mounted on shaft 68. Another gear 70 on shaft 68 drives large gear 72 which is affixed to doffer 8. The gearing just referred to is designed to cause normal rotation of doffer 8 at the same speed as doffer 6.

Gear 56 on shaft 54 also drives a larger gear 74 which is carried by shaft 76. This latter shaft has thereon a smaller gear 78 which meshes directly with a gear 80 of like size, mounted on shaft 82. Shafts 76 and 82 carry the divider rolls, the lower being indicated at 84 and the upper at 86. The remainder of the tape condenser shown herein is conventional and consists briefly of the usual tapes 88, 89, 90 and 91 for dividing the web and transferring it to the several pairs of rubbing aprons 92, 94, 96 and 98. The divided webs are shown after leaving the tapes at 100, 102, 104 and 106 to emerge from the rubbing aprons as roving at 108, 110, 112 and 114. The roving is then wound on the spools 12 in which form it constitutes the finished product coming from the carding machine.

Since both the doffer 8 and the tape condenser 10 are driven by gearing originating with gear 56 on shaft 54, it is believed obvious that the relative speeds between doffer 8 and the tape condenser 10 must remain constant. It is likewise

apparent that any variation in the speed of shaft 18 through actuation of the variable speed mechanism 16 will cause a change in the speeds of belts 18 and chain 20 but the relative speeds between these elements will remain constant.

On the other hand, however, if the speed of output shaft 54 of the variable drive mechanism 22 is varied in relation to the speed of the input shaft 50, it is apparent that there will follow a corresponding relative change in speeds between the doffer 8 and tape condenser 10 on the one hand and the speed of cylinder 4 on the other. In other words, any change in the setting of variable speed mechanism 16 will slow down or speed up cylinder 4, doffer 8 and tape condenser 10 correspondingly, whereas a change in the setting of variable speed mechanism 22 while causing no relative change between doffer 8 and tape condenser 10 will cause a change in the relative speeds between these two elements and cylinder 4.

It is believed apparent, therefore, that while the finisher card is in operation with the variable speed mechanism 16 maintained at any given setting, adjustment of the hand wheel 52 of variable speed mechanism 22 will at once cause a corresponding change in surface speeds between the clothing of cylinder 4 and doffer 8.

Doffer 8 normally runs at a low peripheral speed in relation to cylinder 4. Any further slowing down of the doffer will result in more fibers accumulating on the clothing of the doffer for any unit of circumferential distance with the further corresponding result that the weight of the web removed from the doffer by comb 116 will be correspondingly heavier and hence the roving 108, 110, 112 and 114 leaving the rubbing aprons will likewise be correspondingly heavier per unit of length. That is to say, any slowing down of doffer 8 will immediately produce correspondingly heavier roving, thus changing the count of the roving in accord with the change in relative speeds between doffer 8 and cylinder 4.

On the other hand, if the hand wheel 52 is actuated in the opposite direction so that output shaft 54 is speeded up in relation to input shaft 50, then there will be a corresponding increase in the peripheral speed of doffer 8 in relation to that of cylinder 4, thereby at once producing a lighter webb and correspondingly a less weight of roving in a given unit length. Thus, speeding up of doffer 8 will produce a lighter roving.

From the foregoing explanation the operator of the carding machine may at any time check the count of the roving that is being fed to the spools 12 from the tape condenser 10. If it is not exactly as desired, the operator may then by suitable rotation of hand wheel 52 immediately vary the count up or down as needed without interfering in any way with the general operation of the card. That is to say, it is unnecessary to make any change in the rate at which the fibers are being initially fed to the machine nor is it necessary to stop the machine to effect a gear change at any place which has heretofore been required if the count of the roving was to be varied. It will further be understood that the resulting change in the count of the roving occurs almost immediately following the shifting of the output speed of the variable speed mechanism 22. That is, the change in count becomes apparent as soon as the fibers that are picked up by doffer 8 from cylinder 4 following the speed adjustment have reached the spools 12. This is a matter of seconds and enables the operator to make at once a further

5

sampling and check of the count so that if further adjustment is needed it may be undertaken immediately.

While the variable speed mechanism 16 could be omitted in that it takes no part in varying relative speeds between cylinder 4 and doffer 8, still it is preferred that it be included so that the entire finisher card may be set to operate at the most desirable speed with respect to the breaker card whose production is fed to the finisher card. Having once set the cylinders 2 and 4 operating at the proper speed, the control of the count of the roving is then solely up to the adjustment of the variable speed mechanism 22 under control of hand wheel 52.

When particular types of fibers are being carded with the machine operating at known speeds, it will be possible to determine by preliminary experimentation and by the use of suitable indicators on the hand wheel 52 the amount of change in speed to be made between cylinder 4 and doffer 8 and tape condenser 10 to produce a desired change in the roving count. That is, if the operator upon sampling the roving finds that it is, for example, one percent below the required weight then he will know that by rotating hand wheel 52 in the direction and to the degree determined by the aforesaid experimentation, the resulting decrease in speed of the doffer and tape condenser with respect to cylinder 4 will result in an increase in the weight of the roving sufficient to overcome the one percent deficiency and thereby bring the weight of the roving to the required count immediately by a single adjustment.

In the absence of predetermined knowledge of the adjustment required of the variable speed mechanism 16 to produce particular changes in the weight of the roving then it will be necessary to bring the roving to the required weight by the trial and error method, but this may be done quickly and while the card continues in operation.

Changes in speed between the cylinder and doffer and tape condenser can be conducted to any degree of fineness because of the continuously variable drive in unit 22 that provides an infinite number of speed ratios without steps, all achieved through rotation of hand wheel 52.

It is our intention to cover all changes and modifications of the example of the invention herein chosen for purposes of the disclosure which do not constitute departures from the spirit and scope of the invention.

We claim:

1. The method of changing the count of roving produced by a carding machine having in series a cylinder, doffer and tape condenser, comprising the steps of varying by continuous degrees, while said machine is in operation, the relative speed of said doffer with respect to said cylinder while maintaining the relative speeds of said doffer and tape condenser.

2. The method of changing the count of roving being produced by a carding machine having a cylinder, doffer and tape condenser comprising the steps of simultaneously changing the relative speeds of said doffer and tape condenser with respect to said cylinder whereby the weight of fibers per unit length being fed from said doffer to said tape condenser will be varied in accord with the change in relative speed between said doffer and cylinder, thereby to vary the count of roving being produced by said tape condenser.

3. The method of maintaining the required

6

count of roving produced by a carding machine having in series a cylinder, doffer and tape condenser, said method comprising the steps of selecting a sample of roving as it comes from said tape condenser, testing said roving for its count and noting the discrepancy between said tested count and the required count, progressively varying the speed of said doffer and tape condenser simultaneously with respect to the speed of said cylinder while the machine is in operation to a degree estimated to produce a web flowing from said doffer of a weight that will result in roving produced by said tape condenser of the correct count and then testing said roving produced after said progressive varying of relative speeds between said doffer and tape condenser and cylinder to determine the count produced in accord with the new speed of said doffer and tape condenser and thereafter if necessary making additional progressive relative adjustment of speeds between said doffer and tape condenser and said cylinder while the machine continues in operation until the required count is reached.

4. Means for varying the count of roving produced by a carding machine in which said machine comprises the elements of a cylinder, doffer and tape condenser in series, said roving varying means comprising a principal drive for said cylinder, doffer and tape condenser which principal drive maintains a constant relative speed between all of said elements and a variable speed drive mechanism interposed between said principal drive and said doffer and tape condenser whereby upon adjustment of said variable speed drive mechanism the relative speeds of said doffer and tape condenser may be maintained with respect to each other but varied simultaneously with respect to said cylinder.

5. Means for varying the count of roving produced by a carding machine as set forth in claim 4, said variable speed drive being of the continuously variable type whereby variations in speed between said doffer and cylinder may be made in sufficiently small increments to vary the count of the roving to any small or large degree required.

6. A carding machine comprising a finisher card having at the end thereof in series the elements of a cylinder, doffer and tape condenser, a source of power and means for driving said cylinder, doffer and tape condenser by which the relative speeds of said elements will be maintained constant with respect to each other, a variable speed mechanism interposed between said power source and said drive for said cylinder, doffer and said tape condenser whereby the absolute speeds of said elements may be varied while maintaining constant relative speeds, a second variable speed mechanism interposed between the drive to said doffer and tape condenser whereby the relative speed of the latter two elements may be varied with respect to the speed of said cylinder.

7. Driving means for a carding machine which machine comprises a cylinder, doffer and tape condenser in series, said means comprising a motor, an infinitely variable speed drive connected to said motor for varying the speed of the output shaft, a pulley on said output shaft, a pulley on said cylinder and a belt between said pulleys for driving said cylinder, a first sprocket on said output shaft, a second infinitely variable speed drive with a sprocket on its input shaft and driven by a chain from said first sprocket, an output shaft from said second infinitely variable speed drive having a gear thereon, additional

gearing driven thereby for causing rotation of said doffer and actuation of said tape condenser, said second infinitely variable speed drive providing means operable while said carding machine is running for varying the relative speed of said doffer with respect to said cylinder while maintaining constant the relative speeds of said doffer and said tape condenser.
